UNITED STATES PATENT OFFICE.

WILLIAM C. TIEMANN, OF PHILADELPHIA, PENNSYLVANIA.

DEODORIZER.

1,123,036.

Specification of Letters Patent.

Patented Dec. 29, 1914.

Application filed February 15, 1913. Serial No. 748,693.

To all whom it may concern:

Be it known that I, WILLIAM C. TIEMANN, a citizen of the United States, residing at Philadelphia, in the county of Philadelphia and State of Pennsylvania, have invented certain new and useful Improvements in Deodorizers, of which the following is a specification.

The principal object of the present invention may be said to reside in the providing of a simple, efficient and comparatively inexpensive deodorizer calculated with one filling to give off disinfecting fumes in an even and steady manner for a given time, by capillary attraction.

Other and further objects reside in the providing of general details of construction and arrangement of parts.

The invention consists of the improvements hereinafter described and finally claimed.

The nature, characteristic features and scope of the invention, will be more fully understood from the following description, taken in connection with the accompanying drawing, forming part hereof and in which:

Figure 1, is a view in elevation of the device of the invention, Fig. 2, is a similar view partly sectioned and illustrating the same in application to a supporting structure, and Fig. 3, is a view of the under side of the removable cap shown in the foregoing figures.

Referring to the drawings, the deodorizer of the invention, generally speaking comprises a two-part device of which one part constitutes a container 10, and the other a removable closure or cap 11. In practice, the container 10, is made from glass, porcelain or other nonporous material and the cap 11, from a composition of plaster-of-Paris, powdered alum and fine sand, although other porous material may be employed. This composition is preferable because once the cap 11, is saturated with the deodorizing material employed the alum particles are dissolved thereby rendering the cap very porous. As shown in the drawings, the container 10, is generally bulb-shaped and is provided at its top with a screwthreaded neck 12. The container is further provided with a generally concaved annular portion 13, adapted to receive the closed end of a metallic band 14, the free ends of which band are turned over at right angles and apertured to receive securing me-

diums as, screws 15, in order that the device may be supported upon a suitable structure 16. The cap 11, is shown as being cylindrical in shape, is closed at its top and is cupped out upon its under side, which cupped out portion terminates in an upwardly extending central cylindrical opening 17. For some deodorizing materials employed it may be necessary to provide very minute air ports 21, in order to properly induce capillary attraction. Fitted to the cupped out portion of the cap is an inverted generally cup-shaped centrally apertured metallic lining 18. This lining 18, is provided internally with a screw threaded portion 22, for coöperating with the screw threaded neck of the container 10, and is further perforated as at 19, which perforations are shown as being arranged concentrically with the central opening. Contained within the opening 17, of the cap 11, is one end of a wick 20, which may be tubular and is passed through the central opening of the lining 18, and extends into the container 10.

In manufacture, the parts 11, 18, and 20, are assembled, while the porous material is still plastic, so that when the latter sets or hardens the parts are united together.

In operation, suitable deodorizing or disinfecting material is placed within the container 10, and the cap 11, screwed to place. The material within the container, by capillary attraction, finds its way to the porous cap, saturates the same and is given off therefrom in even and steady fumes. In this connection it is to be observed that the apertures 19, serve to assist in permitting fumes within the container finding their way to the atmosphere through the cap 11.

It is to be noted that by means of this construction and arrangement of parts one filling of the container will serve to insure the giving off of fumes for a given period of time in a steady and even manner in contradistinction to the giving off of very pungent odors at first with depreciable decrease thereof in a few hours' time as is customary with deodorizers now upon the market.

What I claim is:

1. A deodorizer comprising a non-porous liquid container, a porous cap therefor, said cap having a closed top and a cupped out portion upon its under side, a metallic lining for the cupped out portion and a wick secured to the cap centrally thereof and im-

mediately adjacent the cap top and extended through said lining into the container.

2. A deodorizer comprising a non-porous liquid container, a porous cap removably fitted thereto, said cap having a closed top and a cupped out portion upon its under side, a perforated metallic lining for said cupped out portion and a wick fitted to said cap centrally thereof and immediately adjacent the cap top and extended through said lining into the container.

3. A deodorizer comprising a liquid container of non-porous material, having a screw-threaded neck, a porous closure hav-

ing a screw threaded metallic lining for co-operating with the screw threaded neck, said lining having a central opening and a series of perforations therearound and a wick embedded within said closure centrally thereof and immediately adjacent the closure top and extended through the central opening of the lining into the container. 20

In testimony whereof, I have hereunto signed my name.

WILLIAM C. TIEMANN.
